(57) **CLAIM**

The ornamental design for a fiberoptic network tester, as shown and described.

DESCRIPTION

FIG. 1 is a perspective view of a first embodiment of a fiberoptic network tester showing my new design;

FIG. 2 is a front plan view thereof;

FIG. 3 is a right side elevation view thereof;

FIG. 4 is a left side elevation view thereof;

FIG. 5 is a rear plan view thereof;

FIG. 6 is a top elevation view thereof;

FIG. 7 is a bottom elevation view thereof;

FIG. 8 is a perspective view of a second embodiment of a fiberoptic network tester showing my new design;

FIG. 9 is a front plan view thereof;

FIG. 10 is a right side elevation view thereof;

FIG. 11 is a left side elevation view thereof;

FIG. 12 is a rear plan view thereof;

FIG. 13 is a top elevation view thereof; and,

FIG. 14 is a bottom elevation view thereof.

The broken lines showing in FIGS. 1-14 are for illustrative purposes only and forms no part of the claimed design.
